CLAIM

The ornamental design for a coffee capsule storage display rack, as shown and described.

DESCRIPTION

FIG. 1 is a front, top perspective view of a coffee capsule storage display rack, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is another perspective view of the coffee capsule storage display rack, shown in an environment of use. The broken lines in FIG. 9 showing coffee capsules illustrate environment and form no part of the claimed design. All other broken lines show portions of the coffee capsule storage display rack that form no part of the claimed design.
